UNITED STATES PATENT OFFICE.

THOMAS RIGBY, OF DUMFRIES, SCOTLAND, ASSIGNOR TO WETCARBONIZING LIMITED, OF LONDON, ENGLAND.

PEAT GASIFICATION.

1,233,606.

Specification of Letters Patent.

Patented July 17, 1917.

Application filed August 11, 1914. Serial No. 856,254.

To all whom it may concern:

Be it known that I, THOMAS RIGBY, a subject of the King of Great Britain and Ireland, and residing at 61 Loretburn street, 5 Dumfries, Scotland, have invented certain new and useful Improvements in Peat Gasification, of which the following is a specification.

This invention relates to the gasification 10 of peat with recovery of by-products, and has particular reference to the utilization of peat which has had its water rendered more freely expressible by heat treatment, such as wet-carbonization.

15 In the gasification of fuels such as coal in by-product recovery gas plant, for instance of the Mond type, provided a sufficient proportion of steam is introduced into the producer no difficulty is experienced in 20 securing a gas of steady calorific value and in maintaining efficient by-product recovery despite considerable changes in the condition of the fuel fed into the producer, and especially as regards changes in moistness 25 such as occur in materials like colliery refuse.

Now I have ascertained that different 30 conditions present themselves in the gasification of peat, and that to secure constancy in gas composition and maintain efficient by-product recovery the fuel entering the producer must be maintained as far as possible in the same condition, and that in particular a steady moisture content must as far 35 as possible be maintained. This difference in behavior between coal and peat must presumably be attributed to the difference in the volatile matters present in the respective fuels.

40 This invention consists in a method of gasifying (with by-product recovery) peat fuel in different conditions, and especially as regards moisture content, in which the average condition of the fuel entering the 45 gas producer is maintained, as far as convenient, constant by controlled proportionate admixture of the different grades of the fuel.

This invention consists more particularly 50 in a method of the kind described for gasifying mixtures of briquetted peat and press cakes of peat as are described in U. S. patent application Serial No. 712,745, filed 1st August 1912, according to which the admixture is effected by automatically measur-

ing out, preferably in a continuous manner, for admixture, the two forms of the fuel in predetermined proportion variable with the respective moisture content and thereafter thoroughly admixing, also preferably in a 60 continuous manner, these measured out quantities.

Referring now to the accompanying drawings:

Figure 1 shows diagrammatically an installation suitable for carrying the invention into effect, while

Fig. 2 shows to an enlarged scale the outlet end of the bunkers shown in Fig. 1.

In applying the invention to the gasification of admixtures of press cakes of wet carbonized peat having a water content of from 65 to 70% with briquets of the same material having a water content of about 5%, the press cakes are taken from the filter 70 presses by a conveyer *a* to a rotary screen *b*, through which the fine material passes by way of a duct *c* to disintegrators *d* to be 75 thereafter briquetted. The larger lumps of the press cake passing over the screen *b* fall into a bunker *e*, which is preferably 80 provided with a duct *f* connected with the duct *c* in order that any excess of material not required in the producer shall be passed to the disintegrators *d*. At its outlet end 85 the bunker *e* is provided, as shown to an enlarged scale in Fig. 2, with a sliding plate *g* which, by means of a tightening handle *h*, can be fixed at any desired height above the 90 table of a jig conveyer *j* for the purpose of varying the depth of material delivered from the bunker *e* to the jig conveyer and hence the quantity thereof measured out by the latter per stroke. The table of the jig conveyer is reciprocated by a connecting rod *k* 95 attached to a crank *m* on a shaft driven by gearing *n* and belting *o* from an electric motor *p*.

The jig conveyer *j* empties itself into a 100 hopper *q* and preferably into a second rotary screen *r*, in order that any dust produced during the measuring operations shall not pass to the producer where it might be objectionable, but be disintegrated, and thereafter briquetted. The remaining 105 larger lumps of material are taken by a conveyer *s*, and delivered to a hopper *t* where they meet the other constituent, in this case the peat briquets, whereupon admixture is effected on a conveyer *t* by which 110

the charge is carried forward to the producers or store supplying the same.

The briquets to be admixed with the press cakes have usually been obtained from 5 wetcarbonized peat which, after having been filter pressed, disintegrated, further dried, as for example by flue gases to a water content of about 5%, has been briqueted. Such briquets are lifted by a conveyor 10 *u* into a bunker *v* feeding a jig conveyor *w* likewise driven by an electric motor *x*, through belting *y*, gearing *z*, and a crank and connecting rod 1 and 2. The bunker *v* is also provided with a plate *g*, 15 arranged in the manner illustrated in Fig. 2 for the purpose of regulating the quantity of material delivered during each stroke of the jig conveyor. As before, the measured out material is before admixture 20 preferably screened in a rotary screen 3, through which the fine material passes to disintegrators 4, to be thereafter briqueted; while the larger lumps of material pass over to the hopper *i* where, as already mentioned, 25 they meet the press cakes from the bunker *e* and are carried forward by the conveyors *t* to the producer or store.

For the purpose of enabling a constant ratio to be maintained between the respective speeds of the two jig conveyors *j* and *w*, 30 the motors *p* and *x* driving the same are suitably interconnected, as for instance by arranging such motors in parallel on the same mains 5, and rigidly connecting the 35 handles 6 and 7 of their respective starters 8 and 9 by a bar or the like 10.

In using such an apparatus, a producer 40 charge of the desired average moisture content is obtained by adjusting the plate *g* of the bunkers *e* and *v* respectively, at such a height above the table of the jig conveyors *j* and *w* that the depth of the material delivered thereon gives the necessary proportion 45 of press cakes to briquets. If the speeds of the jig conveyor *j* and *w* remain constant, the producer will be charged with fuel at a constant rate, and the latter can thus be varied without in any way altering the average moisture content of the charge, 50 by simply varying the speed of the two jig conveyors, while maintaining a constant ratio between such speeds, as by operating the bar 10 by which the starter handles 6 and 7 are connected.

If preferred, the two jig conveyors may 55 be interconnected mechanically, and driven by means other than electric motors, while in addition, any preferable form of quick return mechanism may be employed for reciprocating the tables of the jig conveyors.

It will be further understood that the 60 above arrangements are only described by way of example, as being suitable where the producer charge is a mixture of press cakes and briquets of wetcarbonized peat. Con-

sequently the apparatus employed for carrying the invention into effect may be considerably modified to suit the particular nature of the peat, or of the mixture supplied to the producer, provided the average 70 moisture content of the charge can be conveniently controlled within predetermined limits.

Having now described my invention, what I claim as new and desire to secure by Let- 75 ters Patent is:—

1. Method of forming a peat fuel mixture for gas producers consisting in feeding forward a stream of relatively moist peat fragments, feeding forward a second stream of 80 such substance in a relatively dry condition and adjusting the relative proportions of said two streams so as to produce when combined a feed of a desired uniform water content. 85

2. Method of forming a peat fuel mixture for gas producers consisting in forming a gaged moving stream or feed of peat fragments in a relatively moist condition, forming a second feed of relatively dry peat sub- 90 stance having a velocity which is constantly related to that of the first feed and a volume adapted on admixture therewith to produce material of a desired water content and mingling said two feeds for the pur- 95 pose set forth.

3. Method of forming a peat fuel mixture for gas producers consisting in forming a gaged moving stream or feed of peat press- 100 cakes, forming a second feed of peat briquets having a velocity which is constantly related to that of the first feed and a volume adapted on admixture therewith to produce material of a desired water content, and mingling said two feeds for the 105 purpose set forth.

4. Method of forming a peat fuel mixture for gas producers consisting in forming a gaged moving stream or feed of peat press- 110 cakes of about 68 per cent. water content, forming a second feed of peat briquets of 5 per cent. water content adapted on admixture with said first feed to produce material of a desired water content, and mingling said two feeds for the 115 purpose set forth.

5. A method of forming a peat fuel charging mixture for gas producers, consisting in forming a gaged moving stream or feed of peat fragments in a relatively moist 120 condition, forming a second feed of relatively dry peat substance having a velocity which is constantly related to that of the first feed and a volume adapted on admixture therewith to produce material of a de- 125 sired water content, mingling said two feeds and regulating their constantly related velocities to supply any required volume of fuel having a uniform distribution of moisture throughout its mass. 130

6. A method of forming a peat fuel charging mixture for gas producers, consisting in forming a gaged moving stream or feed of peat press-cakes of about 68 per cent. water content, forming a second feed of peat briquets of about 5 per cent. water content having a velocity which is constantly related to that of the first feed and a volume adapted on admixture therewith to produce material of a desired water content, mingling said two feeds and regulating

their constantly related velocities to supply any required volume of fuel having a uniform distribution of moisture throughout its mass.

15

In testimony whereof I have signed my name to this specification in the presence of two subscribing witnesses.

T. RIGBY.

Copies of this patent may be obtained for five cents each, by addressing the "Commissioner of Patents,
Washington, D. C."

It is hereby certified that in Letters Patent No. 1,233,606, granted July 17, 1917, upon the application of Thomas Rigby, of Dumfries, Scotland, for an improvement in "Peat Gasification," an error appears in the printed specification requiring correction as follows: Page 2, strike out lines 77, 86, 97, and 107, claims 1, 2, 3, and 4, and insert the words *A method of forming a peat fuel charging mixture*; and that the said Letters Patent should be read with this correction therein that the same may conform to the record of the case in the Patent Office.

Signed and sealed this 4th day of September, A. D., 1917.
